EXPANSIBLE HOUSE TRAILER

Zella M. Seidel, Newberg, Oreg.

Application July 26, 1957, Serial No. 47,104

Term of patent 14 years

(Cl. D14—3)

Fig. 1

Fig. 2

I claim:

The ornamental design for an expapsible house trailer, as shown.
